FLOW CONTROLLING DEVICE FOR BOTTLES

Roy L. Luce, Chicago, Ill.

Application June 14, 1941, Serial No. 398,091

4 Claims. (Cl. 215—15)

This invention relates to improvements in devices of the class which are designed to permit pouring from but prevent refilling of liquid containers. Such devices are attached to the outlets or necks of the containers after the containers have been filled, and thus provide what are popularly referred to as "non-refillable bottles."

These devices have their inception in the desire by bottlers of relatively valuable liquids, such as fine liquors, to protect themselves against refilling of the bottles with spurious contents and the palming off of such contents as the genuine liquid because contained in a genuine bottle.

A practical non-refillable bottle device must meet two major requirements: (a) it must afford reasonably effective protection against refilling of the bottle, and (b) it must be made and assembled with the bottle at a small enough cost, proportionate to the value of the contents, to warrant its use. The major problem has always been to reconcile these factors and strike a satisfactory balance.

Where prior devices have purported to be effective to prevent refilling of the bottle, the cost of manufacture, and often assembly with the bottle, has usually been prohibitive. On the other hand, where the devices could be manufactured and assembled with the bottle at a permissible cost, there has usually been a sacrifice in efficiency.

In this connection, much attention has been devoted in prior devices to the design of one-way flow valves of numerous styles and types of action. The difficulties in designing such valves arise from a combination of factors such as flow sensitivity, proper distribution and balance of valve weight, manufacturing tolerances, selection of materials, accessibility for tampering, and the like.

One way in which the devices relying upon valve action, and particularly the action of a ball valve, have been defeated, is to take advantage of the adhesive qualities of residue material which may be left after evaporation of the liquid to hold the valve open and thus permit a free return flow of liquid past the valve. In whiskey, for example, caramel forms one of the ingredients and leaves an adhesive residue upon evaporation of the small amount of whiskey which invariably remains in any such device after pouring.

My invention has, as the principal aim, to avoid the need for any relatively movable parts in a non-refillable bottle device.

Another object of the invention is to provide a device of this character which utilizes the surface tension of a liquid and air pressure to obstruct refilling of the bottle.

5 Another object of the invention is to construct a device of this general character having a minimum of simple parts which may be cast or molded at low cost from a metal or plastic material which is unaffected by the liquid to be dispensed from the bottle.

10 Another object of the invention is to combine in a device of this type the features of effective prevention of refilling of the bottle, and low cost of manufacture and assembly with the bottle.

15 Other objects and advantages of my invention will appear more fully from the following description and from the accompanying drawing, in which similar characters of reference 20 indicate similar parts throughout the several views.

In the drawing:

Fig. 1 is a fragmentary perspective view showing the neck of a bottle which has one of my 25 flow-controlling devices mounted therein;

Fig. 2 is an enlarged longitudinal sectional view through the bottle neck and the device showing the same in pouring position;

Fig. 3 is an enlarged longitudinal sectional view 30 through the bottle neck and the device in upright position, showing means such as a hose attached to the neck, as might be used in an attempt to refill the bottle;

Fig. 4 is a side elevational view of the inner 35 structure of the device with the outer casing broken away and in section; and

Fig. 5 is a top plan view of the device.

Having particular reference to the drawing, a device embodying the features of my invention 40 is preferably in the form of a self-contained unit 10 constructed to be secured permanently within the neck 11 of a bottle 12. The unit 10 comprises an elongated tubular casing 13 which houses a shorter cylindrical body or core 14 of 45 substantially smaller diameter. The casing 13 may be of any preferred external shape conformable with the shape of the bottle neck 11, but is preferably internally cylindrical.

The outer diameter of the casing 13 is slightly 50 less than the inner diameter of the neck 11 to permit the interposition of a tubular sealing gasket 15 which may be formed of a compressible material such as cork. The original thickness of the gasket 15 is greater than the space into which 55 it must fit between the casing 13 and the bottle

neck wall so that in assembly it is tightly compressed. This acts to hold the unit 10 tightly in place.

In order to prevent removal of the unit 10 from the bottle neck 11 without at least destruction of the sealing gasket 15, the latter is cemented to both the casing 13 and the bottle neck 11. If preferred, the sealing gasket 15 may be omitted and the casing 13 cemented directly to the bottle neck 11, or any other suitable means may be used for connecting the unit permanently within the bottle neck.

The core 14 is rigidly connected in concentric relation within the casing 13 by means of a set of radial vanes 17. These vanes, herein three in number, identified as A, B and C (Figs. 2 and 4), are of spiral form and extend about the core 14 in equally spaced parallel relation to form liquid flow passages 18 of substantial cross-sectional flow area. The outer ends of the vanes 17 terminate symmetrically coextensive with the outer ends of the casing 13 and the core 14 (Fig. 5), while at their inner ends the vanes terminate short of the inner end of the core 14.

The length and pitch of the vanes 17 is preferably such as to carry each of them, and thus each of the passages 18, in internested relation not substantially less than a convolution around the core 14. As a result, the inner and outer ends of each of the passages 18 are in respective substantially longitudinal alignment and a section of each of the three vanes intervenes as a baffle between the ends of each of the passages. This relationship is readily apparent in Fig. 4, which reveals to view the opposite ends of the passages 18 between the vanes A and B and the vanes B and C, while the ends of remaining passage 18 between the vanes A and C are located on the opposite side of the core 14. The spiral arrangement and triple baffle structure of the vanes 17 prevent passage of a tampering instrumentality through the device. Another important function of the spiral vane and passage structure is to assist in preventing refilling of the bottle, as will be presently described.

Means fixedly located inwardly of the inner ends of the vanes 17 provide a novel liquid trap which permits pouring of liquid from the bottle 12 through the unit 10, but prevents refilling of the bottle. The trap is constructed to operate without any moving parts and comprises an upturned substantially frusto-conical flange 19 at the lower end of the casing 13 which opens upwardly at its reduced end into an inverted cup-shaped baffle member 20 formed, in this instance, integrally with the lower end of the core 14 spaced from the lower ends of the vanes 17. The baffle member 20 is of larger diameter than the upwardly extending end or rim of the flange 19 and has the lower edge of its downturned peripheral flange 21 located in radially spaced, preferably concentric, relation to the edge of the flange 19.

Through this arrangement, the flange 19 forms an annular channel 22 facing upwardly in the direction of discharge or pouring flow of liquid from the bottle and is thus adapted to catch returning liquid which fills up to and engages the edge of the baffle flange 21. The trapped liquid closes the gap between the edge portions of the flanges 19 and 21 and forms a meniscus 23 across the gap. The air trapped within the bottle 12 by this closing of the only opening to the outside acts upon the meniscus 23 to prevent return flow of the liquid past the flange 19 and into the bottle. It has

been found that the surface tension of the meniscus 23 will prevent return flow of liquid even though there may be some longitudinal spacing between the edges of the flanges 19 and 21, rather than the concentric relation as shown in the preferred illustrated form. Where there is such longitudinal spacing, the meniscus tilts up to meet the higher edge of the flange 21, instead of being substantially horizontal as seen in Fig. 3.

The flow-preventing action of the trap persists even though the interior of the unit 10 may be filled up with liquid in an attempt at refilling substantially as shown in Fig. 3, for example, where a head of liquid 24 is maintained over the upper end of the vertically standing device by means such as a tube 25 fitted over the end of the neck 11. This prevention of refilling, while the unit is filled with liquid, persists as well in any position to which the bottle may be tilted from a vertical axis.

Neither can the bottle be refilled by supporting it on its side with the level of the liquid 24 reaching only part way up the end of the horizontally lying device. This is so because, in order to reach the inner end of the device, the liquid must flow up hill through one or more of the passages 18 around the core 14. If, to overcome this, the level of the liquid 24 is raised while the neck of the bottle is on its side, return flow of the liquid is blocked by the air pockets which form in the top portions of the spiral passages 18. To allow the air to escape from the passages 18, the bottle must be tilted towards upright position, whereupon the liquid trap formed by the flanges 19 and 21 immediately functions to prevent return flow of liquid into the bottle. The spiral vanes 17 and the passages 18 provide a plurality of traps, in series with the main trap at the inner end of the device, which act when the axis of the device is horizontal.

Any attempt to beat the liquid trap by inserting a tube through one of the passages 18 is frustrated by the baffle member 20 and the radially offset protective relationship of the flange 21 to the flange 19, whereby access is blocked into the opening defined by the flange 19.

In pouring liquid from the bottle (Fig. 2), the bottle is tilted until the inner end of at least one of the passages 18 is at a higher level than the remainder of the passage. Thereupon liquid from the bottle contents will flow past the rims of the flanges 19 and 21 and through the flow space between the peripheral face of the flange 21 and the adjacent wall of the casing 13 into the discharge passage. Because of the longitudinal alignment of the inner and outer ends of the passages 18, the passage having its inner end at the low point to receive the liquid, of course, also has its outer or discharge end at the low point for pouring. As liquid discharges from the bottle, replacement air enters the bottle, as indicated by the arrows in Fig. 2, through the liquid-free passage 18 which has its outer end uppermost and its inner end, therefore, above the level D of the discharging liquid.

For economy of manufacture, the casing 13 and the core 14 may be cast or molded from metal, or thermoplastic non-metallic material, such as glass or a synthetic resin, as separate pieces which may thereafter be soldered, brazed, cemented, or otherwise secured together, depending upon the material from which the parts are made. In this two-piece construction, the vanes 17 are preferably formed integrally with the core 14. If preferred, the casing 13 may be formed from

metal tubing with the flange 19 drawn or spun into shape, and the core 14 and the vanes 17 may be molded or cast from any suitable metal or plastic material.

From the foregoing it will be apparent that my invention provides a non-refillable bottle device which functions satisfactorily without movable valve members. It is of a simple and inexpensive construction, so that it may be produced at a low cost and may be easily and simply permanently assembled with the neck of a filled conventional type of bottle.

While my invention is susceptible of various modifications and alternative constructions, and while I have illustrated and described a certain preferred embodiment, it is to be understood that I do not thereby intend to limit my invention to the specific form disclosed, but contemplate that many modifications and substitutions may be made without departing from the scope and spirit of my invention.

I claim as my invention:

1. In combination in a non-refillable bottle closure device, means arranged to be permanently secured in flow-controlling relation to the neck of a bottle, an annular upstanding flange defining a discharge port and an annular channel facing in the direction of discharge flow surrounding said port, a substantially horizontal fixed baffle member spaced above said flange, an annular flange extending downwardly from said baffle member and having its edge at substantially the same level as and being in spaced concentric relation to the edge of said upstanding flange to provide a relatively narrow annular gap for the passage of liquid contents of the bottle when pouring, said channel being adapted to catch returning liquid and hold such liquid in sealing relation across said gap to form a meniscus upon which air trapped within the bottle acts to prevent the returning liquid from entering through said annular gap to the interior of the bottle, and means preventing tampering access to said gap, said last mentioned means including a cylindrical core extending concentrically from said baffle member to the discharge end of the device and a plurality of one revolution spiral passageways surrounding said core and alternating as liquid discharge and replacement air vents in accordance with the direction in which the bottle is tipped in pouring, the passageways forming liquid traps preventing return flow of liquid into the bottle through the device when the bottle is lying on its side or is tilted over between such lying position and the upright or nearly upright position where liquid trapped in said channel closes said gap to form the meniscus as aforesaid.

2. In combination in a non-refillable bottle closure device, means for securing the device in permanent flow-controlling relation to the neck

of a bottle, means at the inner end of the device for permitting discharge flow only of liquid from the container while preventing return flow, and means within the outer part of the device assisting in preventing return flow under certain conditions and providing a baffle structure to prevent access into the bottle comprising a fixed central core and a plurality of spaced parallel spiral vanes surrounding said core and defining at least three equidistant spaced spiral passages about the core, the pitch and length of said vanes being such that the passages describe approximately one convolution about the core and have their inner and outer ends approximately in alignment so that in pouring from the bottle the same passage will have both its inner and outer ends at the low side of the bottle and at least one of the passages in any pouring position of the bottle will have both of its inner and outer ends at the high side of the bottle to provide an air vent.

3. A non-refillable bottle closure device as defined in claim 2 in which the arrangement of the baffle vanes is such that each vane is fully interposed between the inner and outer ends of each 15 of the passages as a multiple protection against driving a tampering instrumentality straight through from the outer to the inner end of any one of the passages.

4. A unitary capsular non-refillable bottle closure device comprising a cylindrical tubular shell, a generally frusto-conical annular flange integral with the lower end of said shell and projecting a short distance upwardly within the shell, said flange defining a reduced diameter discharge 20 flow port for the lower end of the shell and providing an annular channel within the shell opening in the direction of discharge flow, and a cylindrical core concentric with said port and having an inverted cup-shaped baffle rigid with its lower end, said baffle having a downwardly extending annular peripheral flange of a diameter intermediate the internal diameter of said shell and the port edge diameter of said shell flange, said baffle flange having its lower 25 edge concentrically related to the port edge of the shell flange at approximately the same horizontal plane so as to dip into liquid trapped in said channel to enable the formation of a return-flow preventing meniscus trap between the flange edges, the core having a plurality of equally spaced radially extending one-convolution spiral 30 vanes bridging the space between the core and the internal wall of the shell and supporting the core fixedly within the shell, said vanes providing alternative discharge flow passageways and replacement air vents as well as auxiliary return 35 flow traps complementary to the flow trap provided by said channel and permitting pouring from the bottle in practically any direction of 40 tilting of the bottle.

ROY L. LUCE.
